Primary Examiner — T Chase Nelson*Assistant Examiner* — Kelly L Gross*(74) Attorney, Agent, or Firm* — Knobbe, Martens, Olson & Bear, LLP(57) **CLAIM**

The ornamental design for a physiological nose sensor, as shown and described.

DESCRIPTION

FIG. 1 is a perspective view of a physiological nose sensor embodying our new design;

FIG. 2 is another perspective view thereof;

FIG. 3 is top view thereof;

FIG. 4 is bottom view thereof;

FIG. 5 is a side view thereof;

FIG. 6 is another side view thereof;

FIG. 7 is a front view thereof;

FIG. 8 is a back view thereof; and,

FIG. 9 is another perspective view thereof.

Broken lines, where shown, are used to illustrate portions of the physiological nose sensor that form no part of the claimed design. The broken line human figure in FIG. 9 shows environment associated with the physiological nose sensor in a state of use and also forms no part of the claimed design.
